DESIGN FOR A HORSESHOE GAME DEVICE

Ralph Apichell, Cleveland, Ohio

Application October 21, 1936, Serial No. 65,391

Term of patent 7 years

To all whom it may concern:

Be it known that I, Ralph Apichell, a citizen of the United States, residing at Cleveland, in the county of Cuyahoga and State of Ohio, have invented a new, original, and ornamental Design for a Horseshoe Game Device, of which the following is a specification, reference being had to the accompanying drawing, forming part thereof.

In the drawing, Fig. 1 is a plan view of a horseshoe game device showing my new design; Fig. 2 is a side elevational view thereof; and Fig. 3 is a sectional view taken on the line 3—3 of Fig. 1.

I claim:

The ornamental design for a horseshoe game device, as shown.

RALPH APICHELL.
